US0D1095743S

(12) **United States Design Patent** (10) **Patent No.:** **US D1,095,743 S**
(45) **Date of Patent:** **** Sep. 30, 2025**

(54) **INSECT TRAP**

- (71) Applicant: **E. MISHAN & SONS, INC.**
(72) Inventor: **Debbie Feuerstein**, New Rochelle, NY (US)
(73) Assignee: **E. MISHAN & SONS, INC.**, New York, NY (US)
(***) Term: **15 Years**
(21) Appl. No.: **29/939,185**
(22) Filed: **Apr. 25, 2024**
(51) LOC (15) Cl. **22-06**
(52) U.S. Cl. **D22/122; D22/119; D22/120; D22/123**
(58) **Field of Classification Search**
USPC **D22/119, 120, 122, 123, 199; D26/26; D30/199**
CPC ... **A01M 1/106; A01M 2200/012; A01M 1/14; A01M 1/04; A01M 1/145**
See application file for complete search history.

(57) **CLAIM**

The ornamental design for an insect trap as shown and described.

DESCRIPTION

FIG. 1 is a top right side perspective view of an insect trap showing my design;

FIG. 2 is a rear left side angled perspective view of my design;

FIG. 3 is a left side of my design;

FIG. 4 is a right side view of my design;

FIG. 5 is a front view of my design;

FIG. 6 is a rear view of my design;

FIG. 7 is a top view of my design; and,

FIG. 8 is a bottom view of my design.

The broken lines represent portions of the insect trap that form no part of the claimed design.

1 Claim, 7 Drawing Sheets
